UNITED STATES PATENT OFFICE.

CHARLES G. CANIVET, OF NEW YORK, N. Y., ASSIGNOR TO THE WESTERN CLOCK MANUFACTURING COMPANY, OF LA SALLE, ILLINOIS, A CORPORATION OF ILLINOIS.

DESIGN FOR A CLOCK-CASE.

No. 38,770.

Specification for Design.

Patented Aug. 27, 1907.

Application filed May 31, 1907. Serial No. 376,742. Term of patent 7 years.

To all whom it may concern:

Be it known that I, CHARLES G. CANIVET, a citizen of the Republic of France, residing in the city of New York, in the county of New York and State of New York, have invented a new, original, and ornamental Design for Clock-Cases, of which the following is a specification, reference being had to the accompanying drawing, forming a part thereof.

The figure is a perspective view of a clock case, showing my design.

I claim:

The ornamental design for a clock case, as shown.

CHARLES G. CANIVET.
